POWER-OPERATED TWEEZERS

Floyd V. Schleimer, San Francisco, Calif., assignor to United States Appliance Corporation, San Francisco, Calif., a corporation of California

Application March 13, 1935, Serial No. 10,861

4 Claims. (Cl. 128—355)

This invention relates generally to tweezers such as are employed for plucking hair, and particularly to tweezers which are driven from an available source of power so as to be substantially automatic in operation.

It is an object of the invention to provide a device of the above character which can be readily handled by an operator and which will make possible rapid plucking action with a minimum 10 of discomfort to the subject.

Further objects of the invention can be briefly outlined as follows:—To minimize noise and vibration, such as are common with power-driven appliances; to afford a simple construction which can be readily manufactured and assembled; and to afford a device which will give long useful service with a minimum of maintenance and repair expense.

Additional objects of the invention will appear 20 from the following description in which the preferred embodiment of the invention has been set forth in detail in conjunction with the accompanying drawings.

Referring to the drawings:

25 Fig. 1 illustrates my complete device, including an electrically driven pneumatic pulsator.

Fig. 2 is a cross-sectional detail illustrating connections between the electric motor and other moving parts of the pulsator.

30 Fig. 3 is a longitudinal cross-section, illustrating the applicator which is utilized in conjunction with the pulsator of Fig. 1.

Fig. 4 is a cross-sectional view similar to Fig. 3, but showing a different operating position for 35 the parts.

Fig. 5 is an end view of the applicator, looking towards the forward end of the casing or mounting from which the tweezer elements project.

Fig. 6 is a cross-sectional detail taken along 40 the line 6—6 of Fig. 4.

Referring first to Fig. 1, my device consists generally of a pulsator 10, connected by a flexible tube 11 to an applicator 12. In most instances it is desirable to have the pulsator mounted upon 45 a suitable portable stand, so that it can be readily shifted to a convenient operating position.

The pulsator may vary in details of construction, but in the instance illustrated it consists of an electrical motor 13 carried within a suitable 50 housing 14. By means of an electrical switch 15 the motor can be stopped and started as desired. The parts driven by the motor include a flexible diaphragm 16, the marginal edge of which is clamped to an annular shoulder 17 by 55 means of a removable dome or closure cap 18.

Thus, on one side of the diaphragm 16 there is a closed air chamber 19, which is in communication with the flexible tube 11.

Attached to the center of diaphragm 16 there is a rod 21, which in turn connects to an eccentric mechanism driven by the motor. Thus the motor shaft 22 is shown provided with a worm 23, which engages the worm gear 24. Gear 24 is shown carried by a shaft 26, which also carries the eccentrics 27. A fork 28 is 10 shown journaled upon the eccentrics 27, and is connected to the rod 21. Thus when the motor 13 is operated, diaphragm 16 is vibrated at a suitable rate, as for example about 500 complete cyclic movements per minute. Rod 21 may 15 carry a cup washer 29, engaging the outer face of diaphragm 16 to avoid detrimental abrupt flexing of the same.

The applicator 12 has been illustrated in detail in Figs. 3 to 6 inclusive. It consists of a 20 hollow, elongated casing 31, which can be readily grasped by the hand of an operator and which forms a mounting for the moving parts. This casing can be formed of suitable light material, such as "bakelite." The rear end portion 32 of the casing 31 is in the form of a 25 removable closure cap and serves to grip the marginal edge of a flexible diaphragm 33. The flexible tube 11 can be attached to the coupling tube 34, which in turn communicates with the 30 closed air chamber 36 behind the diaphragm 33. As will be presently explained, it is desirable, but not essential, to afford a pressure spring 37 35 behind the diaphragm 33, tending to flex this diaphragm forwardly in the position shown in Fig. 3.

In the forward end portion of the casing 31, a longitudinal opening 38 is provided, which preferably has parallel side walls and which can be conveniently square in transverse cross-section. 40 Fitted within the opening 38 there is a slide block 39. This block forms a mounting for a pair of projecting tweezer elements 41 and 42, which serve as the operating elements for gripping and plucking hair. Thus, tweezer element 41 is shown attached to the outer end portion of block 39 by rivets or screws 43, while tweezer element 42 is received in a longitudinal slot 44 and is pivotally connected to the block by means of pin 46. The outer co-operating ends 47 and 50 48 of the elements 41 and 42 may therefore move laterally relative to each other, to grip and release the hair. The inner co-operating faces 49 of the end portions 47 and 48 are preferably provided with interfitting grooves or corrugations, 55

as shown in Figs. 3 and 4, so as to afford a better grip upon individual hairs, and to facilitate the release of a gripped hair when the end portions 47 and 48 are moved apart.

5 The tweezer element 42, instead of terminating adjacent the pivot pin 46, is extended inwardly to form in effect an arm 51. By means of a linkage mechanism designated generally at 52, arm 51 is operatively connected to an actuating member or rod 53, which has its rear end attached to the center of diaphragm 33. While various forms of linkage mechanism may be available, the type illustrated utilizes a lever 54, having its one end provided with a pivotal connection 56 to the forward end of rod 53. The other end of lever 54 is pivotally connected to a pin 57, which in turn is carried by the slide block 39. The line of centers of pins 56 and 57 is generally at right angles to the direction of 10 sliding movement afforded between block 39 and the casing 31. Lever 54 also carries a forwardly projecting arm 58, which, by means of a pivotal connection 59, is attached to one end of a link 61. The other end of link 61 has a pivotal 15 connection to the rear end of arm 51. With this type of linkage mechanism, it is evident that when rod 53 moves rearwardly with respect to casing 31, lever 54 and also arm 58 are rotated in a clockwise direction, to swing arm 51 about 20 its pivot 46 in a counter-clockwise direction and thus bring the end portions 47 and 48 of the tweezer elements into hair-gripping position. It is likewise evident that continued rearward movement of rod 53, since it can effect no further movement of arm 51, serves to slide the 25 block 39, together with the tweezer elements and other parts carried by the same, rearwardly into the casing. Conversely, when rod 53 is moved forwardly, its initial movement causes the 30 tweezer elements to move to released position, and then further forward movement of rod 53 causes the block 39 and the tweezer elements to be slid forwardly relative to the casing. Thus, reciprocation of rod 53, through proper limits, 35 serves to move the tweezer elements between hair-gripping and released positions, and in synchronism with such movements the tweezer elements are caused to be continuously projected and retracted with respect to the casing 31.

50 In order to insure proper gripping pressure between the tweezer elements, it is desirable to afford frictioning means acting between the block 39 and the adjacent walls of the casing 31. Such frictioning means has been shown in Fig. 6, in 55 which one side of the block 39 is provided with a recess 66 serving to accommodate a spring 67. This spring is normally under tension so as to frictionally press against the adjacent inner side wall 68 of the casing. Smoother and more reliable operation is also afforded by providing a spring or like bias tending to urge the rod 53 rearwardly relative to the block 39. For this purpose a light compression spring 69 has been shown surrounding rod 53, with the forward 60 end of the spring seated upon the rear end of the slide block 39, and with the rear end of the spring seated upon a fitting 71 which serves to connect the rod 53 to the diaphragm 33.

It has been found desirable to afford some 70 means for ejecting plucked hair from between the tweezers immediately following movement of the tweezers to open position. For this purpose a small tube 72 is shown, having its forward open end terminating between the tweezer elements 41 and 42 and immediately behind the

end portions 47 and 48. As shown in Fig. 6, this tube 72 extends through the forward end portion of block 39 and has its inner end communicating with a slot 73, which in turn extends rearwardly and communicates with the space 74 surrounding the inner end of the slide block. Pressure variations set up in space 74 during operation of the device, by virtue of continued flexing movements of diaphragm 33, accompanied by the more or less out-of-phase reciprocation of block 39, causes recurrent puffs of air to be discharged from the outer end of tube 72, which are so timed as to blow between the end portions 47 and 48 of the tweezer elements at the time these elements move toward release position.

Operation of my device can now be reviewed as follows:—The applicator described with reference to Figs. 3 to 6, inclusive, is connected to the flexible tube 11 and the motor 13 started in operation. Repeated flexing of diaphragm 16, by operation of the motor, causes air trapped in spaces 19 and 36 and within the tube 11, to be recurrently compressed and rarefied. Thus, diaphragm 33 of the applicator is likewise recurrently flexed, in synchronism with the flexing movement of diaphragm 16. Recurrent flexing of diaphragm 33 causes reciprocation of rod 53, to effect the desired operation of the tweezer elements 41 and 42. To briefly review a cycle of operation, commencing with the rod 53 in the position shown in Fig. 3, during the initial part of rearward movement of rod 53 block 39 remains stationary with respect to the casing 31, but rotation of lever 54 forces arm 53 upwardly, as viewed in this figure, to close the tweezer elements. Following such closing of the tweezer elements, continued rearward movement of rod 53 serves to slide the block 39 inwardly with respect to the casing, to effect retraction of the 40 tweezer elements and consequent plucking of the hair gripped. Full rearward movement of rod 53 is illustrated in Fig. 4. Now, as the rod 53 starts forwardly, the first part of its movement rotates lever 54, to swing arm 51 downwardly and thus move the tweezer elements to open or release position. Further continued forward movement of rod 53 causes the block 39 to be slid forwardly, with a projection of the open tweezer elements for a new gripping operation. As has been previously explained, this operation takes place at a relatively high speed, and when the elements are so operated discomfort to the subject is minimized.

With a device constructed as disclosed herein, 55 it has been noted that the suction or rarefaction stroke of the diaphragm 16 appears to exert more force upon diaphragm 33 than the compression stroke. It is for this reason that compression spring 37 has been inserted, to tend to equalize 60 reciprocating forces upon rod 53 for both suction and compression strokes.

A desirable characteristic of my device is that it operates with a relatively small amount of noise and vibration, which I attribute to the fact 65 that power is supplied to the applicator pneumatically rather than by direct mechanical connection. Pneumatic operation is also deemed more desirable than a flexible mechanical drive, because it enables a material simplification in construction, with a long useful life, and without necessity of frequent servicing and repair.

The subject matter disclosed but not claimed herein, is claimed in my co-pending application, Serial No. 48,203, filed Nov. 4, 1935.

I claim:

1. In a device of the character described, a pair of tweezer elements having co-operating hair-gripping end portions, a hollow elongated casing adapted to be grasped by an operator, a block 5 slidably carried within one end portion of said casing, for reciprocating movement in a longitudinal direction, means serving to attach one of said tweezer elements to said block, means 10 forming a pivotal connection between said block and the other one of said tweezer elements, said last-named tweezer element having an arm secured to the same extending rearwardly within the casing, an actuating member mounted in the 15 rear portion of the casing, means serving to rapidly reciprocate said actuating member in a direction longitudinally with respect to the casing, a lever serving to pivotally connect the forward end of said actuating member to said 20 block, an arm carried by said lever, and a link serving to pivotally connect said last-mentioned arm with the inner end of said first-mentioned arm, said first-mentioned arm having limited 25 pivotal movement whereby reciprocation of said actuating member effects sliding movement of said block and also causes relative lateral movement between said tweezer elements.
2. In a device of the character described, a hollow elongated casing adapted to be grasped by the hand of an operator, a pair of tweezer elements slidably carried within the forward end 30 of said casing and projecting therefrom, a diaphragm mounted within the rear end portion of said casing, there being a closed chamber behind 35 said diaphragm adapted to receive periodically varying pneumatic pressures, an actuating member within the mounting, one end of said member being secured to said diaphragm and the other end of said member extending forwardly 40 within the mounting towards said tweezer elements, and mechanism serving to co-operatively connect said member with said tweezer elements and serving to reciprocate the same relative 45 to the mounting and to effect relative lateral movement between the hair-engaging ends of the same.
3. In a device of the character described, a hollow elongated casing adapted to be grasped by an operator, a pair of tweezer elements, means serving to slidably mount said tweezer elements in the forward end portion of said mounting, said last means also enabling relative pivotal movement of said elements between hair-gripping and release positions, actuating means carried within the rear portion of said mounting and serving to effect longitudinal reciprocation of said tweezer elements in synchronism with relative lateral movement of the tweezer elements between hair-gripping and release positions, and means for directing a stream of air between the hair-gripping portions of said 15 tweezer elements.
4. In a device of the character described, a pair of tweezer elements having cooperating hair gripping end portions, a hollow elongated casing adapted to be grasped by an operator, a block 20 slidably carried within one end portion of said casing, for reciprocating movement in a longitudinal direction, means serving to attach one of said tweezer elements to said block, means forming a pivotal connection between said block 25 and the other one of said tweezer elements, said last named tweezer element having an arm secured to the same extending rearwardly within the casing, a flexible diaphragm mounted within the rear end portion of the casing, there being 30 a closed chamber behind said diaphragm adapted to receive periodically varying pneumatic pressures, an actuating member mounted in the casing and having its rear end connected to said diaphragm, a lever serving to pivotally connect 35 the forward end of said actuating member to said block, an arm carried by said lever, and a link serving to pivotally connect said last mentioned arm with the inner end of said first mentioned arm, said first mentioned arm having 40 limited pivotal movement whereby reciprocation of said actuating member effects sliding movement of said block and also causes relative lateral movement between said tweezer elements.

FLOYD V. SCHLEIMER.
